Herrick Aiken of Franklin N.H.
Letters Patent No. 1001, dated May 11th 1858

The schedule referred to in these Letters Patent and making part of the same.

To all whom it may concern:-

Be it known that I, Herrick Aiken of Franklin in the County of Merrimack and State of New Hampshire, have invented or produced a new and original design for a box and I do hereby declare that the following is a full and exact description.

The box is made of straw board or other suitable material in the usual manner, my improvement consists in attaching thereto or covering the box with prints representing a set of twenty awls and tools a wrench and a handle which has a receptacle to contain the awls tools and wrench all of which are shown in the drawings annexed.

The articles represented are my invention and the principle device contained in those articles has been secured to me by letters patent. The box is designed to contain the articles represented thereon and directions and cautions are also printed on the paper with which the box is covered. Boxes heretofore been made and covered with prints representing the articles which they were designed to contain.

2

Des. 1001

therefore I do not claim the principle of covering boxes with prints but I claim the attachment to a box of the particular prints representing my inventions as shown in the drawings and on the box.

Witnesses.
